Inventor:

James William Leary,
By Dodge and Sons,
Attorneys.

UNITED STATES PATENT OFFICE.

JAMES WILLIAM LEARY, OF JERSEY CITY, NEW JERSEY, ASSIGNOR TO AUTOMATIC PACKING & LABELING COMPANY, OF DURHAM, NORTH CAROLINA, A CORPORATION OF NORTH CAROLINA.

BAG.

1,238,411.

Specification of Letters Patent. Patented Aug. 28, 1917.

Application filed April 23, 1915. Serial No. 23,324.

To all whom it may concern:

Be it known that I, JAMES WILLIAM LEARY, a citizen of the United States, residing at Jersey City, in the county of Hudson and State of New Jersey, have invented certain new and useful Improvements in Bags, of which the following is a specification.

My present invention pertains to an improved bag of the "square, satchel-bottom" type.

The object of the invention is to produce a bag of the above type, with a liner of moisture-repellent material, and having no projecting tabs or ears upon the exterior of the bag, whether the bag be in its collapsed or set-up condition.

The bag and the blanks from which it is produced are disclosed in the annexed drawings, wherein:

Figure 1 is a plan view of the outer or bag-blank with the inner or liner-blank imposed thereon;

Fig. 2 a like view after the first and second folds have been made;

Fig. 3 a similar view, wherein the edges of the blank are inturned;

Fig. 4 a perspective view illustrating the manner in which the final fold is made;

Fig. 5 a like view of the two blanks;

Fig. 6 a vertical section of the bag in its collapsed condition;

Fig. 7 a similar view of the expanded or set-up bag;

Fig. 8 a perspective view of the expanded bag viewing the bottom thereof, with a portion broken away; and

Fig. 9 a vertical sectional view through the bottom and one side of the bag.

While both the exterior and liner members contribute to the strength of the bag and enter directly into its make-up, the exterior member, for the sake of clearness in description, will be hereinafter referred to as the bag-blank and the other as the liner, or liner-blank.

The bag-blank is produced from a sheet of suitable material, and comprises two sections 1 and 2, both substantially rectangular in form and in the present instance substantially oblong, though the lower end of 1 is cut out while the upper end of 2 is peaked so as to produce a projecting edge at the top of the bag, see Fig. 6, to facilitate the manipulation of the bag in the opening of the

same. The size of the bag to be produced will, of course, determine the relative width and length of the sections 1 and 2.

The liner blank comprises two sections, 3 and 4, of substantially the same form as the bag blank, section 3 being narrower than section 1, which it overlies, and section 4 being wider than the underlying section 2.

The bag and liner blanks will be scored lengthwise upon the lines (dot-and-dash) 5 and 6, and preferably scored upon the converging lines 7, 7 and 8, 8, lines 7, 7, extending downwardly and outwardly from the junction of line 5 (or 6 as the case may be) and the initial folding line 9, coinciding with the second folding line 10 and score lines 8. Said latter lines extend downwardly and inwardly and merge into score line 5 (or 6) and also the fourth line of fold 11.

Paste or other suitable adhesive, shown in stipple, will be applied to the triangular spaces 12, formed between said scoring lines 7 and 8, the margins of the bag blank and the fold lines 9 and 11. The oppositely-disposed edges or marginal portions of the sections 2 and 4, are designed to be turned inwardly, as shown in Fig. 3, the lines of fold (being the third operation in the formation of the bag) being designated by 14, and coincident with the longitudinal edges of section 1.

Adhesive, shown in stipple, will also be applied to the exposed or outer faces of said inturned portions, or flaps, 13.

The bags are designed to be produced by machinery, and the steps of formation will be as follows:

The scored liner blank will be imposed on the scored bag blank (or they may be scored after placement) and sections 1 and 3 turned or folded upwardly on the initial folding line 9, and then folded back on line 10, or said folds may be simultaneously formed, adhesive being applied to the spaces 12, if it be desired to seal the inturned tabs 15, Figs. 6, 7, 8 and 9. The blanks are then in the position shown in Fig. 2 and the side flaps, 13, are turned inwardly and the lower portions of the sections 1 and 3 of the bag and liner blanks are folded upwardly on the folding line 11 and brought into contact with said flaps 13, to which adhesive has been applied.

Sufficient pressure will, of course, be ap-

plied to cause proper adhesion, and heat may be employed if desired to speed the operation.

The bags when completed and collapsed will be of the form shown in Fig. 6, and when opened, or set-up, will appear as in Figs. 7 and 8, the tabs or ears 15 naturally forming and extending upwardly from the bottom of the bag adjacent the sides, as is clearly shown. While the formation and folding of the parts tends to hold the liner or inner bag in position with the outer bag, the use of adhesive on the spaces 12 causes a positive retention of the liner or inner bag in place.

Paper of a quality to meet the requirements of the purpose for which the bag is to be used will be employed in producing the blanks.

I have referred to the score lines 5 and 6, and scoring upon lines 7, 7 and 8, 8. Such scoring is not absolutely essential to the formation of the bag though its presence enables the bag to be opened or squared up with greater facility.

Having thus described my invention, what I claim is:

1. A square-bottomed, double-walled bag formed from an outer blank having a narrow member and a broad member, produced from a single piece of paper; and an inner blank having similar members, the narrow member being narrower than the corresponding member of the outer blank, while the wider member is wider than the corresponding broad member of the outer blank, the narrow members being of greater length than the broad members, the sides of the wider portions of the superposed blanks being turned inwardly and having the outer faces thereof secured to the edges of the narrow members which are turned upwardly thereover, the narrower members adjacent the point of junction with the wider members, being folded to form a satchel-bottom and produce ears which extend inwardly from the bottom adjacent the sides of the completed bag, when the bag is set up or squared.

2. A square-bottomed bag formed from an outer blank of suitable paper, and a lining blank of moisture - repellent paper; each

blank comprising a broad member and a narrow member, the broad member of the lining blank being broader than the corresponding member of the outer blank, and the narrow member of the lining blank being narrower than the corresponding member of the outer blank, and the narrow members being longer than the broad members, said blanks having alined scoring lines extending throughout the length thereof, spaced respectively a slight distance from the edges of the narrow member of the lining blank, said narrow members being folded upon themselves adjacent the wider members to produce a folded bottom, and the edges of said narrow members being secured to the outer faces of the inturned edges or flaps of the wider members when the narrower members are turned upwardly thereover.

3. A square-bottomed bag formed from an outer blank of suitable paper, and a lining blank of moisture - repellent paper, each blank comprising a wide and a narrow member, the narrower member of the lining blank being narrower and the wide member wider than the corresponding members of the outer blank, said blanks having alined scoring lines extending lengthwise thereof spaced respectively a slight distance inwardly from the edges of the narrow member of the lining blank, the narrow members adjacent the wide members being provided with outwardly-converging scoring lines at each side extending from the longitudinal scoring lines aforesaid, said narrow members of the blanks adjacent the wider members being first folded over the wider members, then backward upon themselves, and then upwardly over the fold thus formed, and over the wide members, being secured at their edges to the outer faces of the in-turned flaps formed along the edges of the wider members.

In testimony whereof I have signed my name to this specification in the presence of two subscribing witnesses.

JAMES WILLIAM LEARY.
